ROTARY HECTOGRAPHIC COPYING MACHINE FOR SELECTIVE IMPRESSIONS

Roland Brown, London, and Leonard Herbert Neville Watton, New Malden, England, assignors to Block & Anderson Limited, London, England, a British company

Application August 31, 1951, Serial No. 244,654

Claims priority, application Great Britain August 31, 1950

28 Claims. (Cl. 101—132.5)

The invention relates to hectographic copying machines whereby copies are taken from a master sheet prepared in mirror-script with a hectographic ink and mounted on the drum of a rotary printing couple so that the lines of text run circumferentially of the drum, the copy sheet moistened with a solvent for the ink being pressed against the drum by a pressure roller forming with the drum a printing couple, and has particular reference to a machine wherein the means for securing a movable master sheet, hereinafter referred to as a clip, is movable in the lengthwise direction of the drum. A machine of this kind is described in British patent specification No. 562,502.

An object of the present invention is to provide a hectographic copying machine capable of taking a number of different selected impressions from a movable master sheet, together, if desired, with an impression from a fixed master sheet, from a fixed feeding position for the work and a fixed delivery position, these operations being carried out with an improved degree of accuracy and an economy of time and movement of both the machine and the operator.

A further object in the invention is to provide improved means for positively driving and controlling the motion of the movable clip in either direction with respect to the drum.

According to the present invention a hectographic copy machine comprises a drum carrying a fixed clip adapted to secure a mask or a printing master and a movable master clip lying lengthwise of the drum and traversable lengthwise thereof when the drum is at rest, the movable clip being behind the fixed clip in the direction of rotation of the drum so that a master secured in the movable clip may be exposed for printing to a variable extent beyond the edge of an overlying master or mask in the fixed clip, and a combined pressure roller and damping unit capable of traversing lengthwise of the drum independently of said movable clip to register with and print from any desired zone of the movable master said zone being defined between the edge of the fixed master or mask and the leading edge of the pressure roller.

In the preferred construction the pressure roller and damping unit is somewhat more than half the length of the drum so that besides taking a number of different impressions of part of a fixed master and any selected adjacent portion of a movable master, it may be moved into another position to take an impression of the fully exposed length of the movable master up to half the length of the drum plus the said adjacent portion of the fixed master.

A further feature of the invention consists in positive driving means to move the movable clip in either direction, such motion being controlled by an escapement mechanism to provide rapid adjustment of the said clip by unitary stepwise movement. In a preferred construction the movable clip is driven by a nut and a lead screw mounted coaxially with and inside the drum and arranged to be coupled to the drum for rotation therewith during the printing operation. It is preferred to employ

2

a power drive both for the clip and the pressure and damping carriage, these being separately controlled through one revolution clutches to provide for single spacing or continuous controlled movement of the clip and the carriage in the appropriate directions.

10 A further features of the invention relates to a construction and arrangement of the individual control devices controlling the motion of the movable clip end of the carriage, and means for coupling the said control devices for dual or single operation so that simultaneous travel of the clip and the carriage can be performed to bring the clip and carriage into their desired relative positions, whilst any further positional adjustment of either the clip or the carriage may be obtained by the individual controls operated separately.

15 A further feature of the invention relates to safety mechanism for interlocking the respective control devices for the drum, the clip and the carriage so that the drum cannot be set in motion at the same time as the clip or carriage or vice versa.

20 A further feature of the invention relates to a movable indicator for displaying the position of the movable clip of the operator, and means for coupling the indicator to the driving means for the clip when the latter is in motion so that correct relationship is maintained between the positions of indicator and clip.

25 Further features of the invention relate to stop means for automatically arresting the carriage or the clip in their end positions, and to stop means provided on the position indicator, said stop means being operated in the end positions of the said indicator to arrest both the indicator and the movable clip.

30 Further features relate to a form of clutch and to a centralizing or locating device cooperating therewith, and adjustable to vary the rest position of the driven member of the clutch.

35 The above and other features of the invention, and the attendant advantages, will be apparent from the following description of one example of a machine embodying the improvements according to the invention, which is shown in the accompanying drawings.

40 Fig. 1 is a part elevation of the right-hand side of the machine.

45 Fig. 2 is a part elevation of the left-hand side of the machine.

45 Fig. 3 is a part plan view showing the framework and the layout of the machine, but omitting the main part of the power transmission and control gear for the drum, for the damping and pressure carriage unit, and for the movable clip, these being shown on a larger scale in Figs. 4 and 5.

50 Fig. 4 is an enlarged plan view of part of the right-hand side of the machine showing details of the control gear for the carriage, the movable clip and the indicator.

55 Fig. 5 is an enlarged plan view of part of the left-hand side of the machine showing the power transmission and control gear for the drum.

65 Fig. 7 is a plan of the pressure roller and damping carriage.

Fig. 7a is a front elevation of an adjustable cam centralizing device employed in conjunction with the clutches for the carriage.

65 Fig. 8 is an end view of Fig. 7.

Fig. 9 is a front elevation of the damper only.

Fig. 10 is a side elevation of part of a clutch control mechanism for the reverse motion of the carriage.

70 Fig. 11 is a side elevation of part of the clutch control mechanism for single spacing and continuous travel of the carriage in the forward direction.

Fig. 12 is a partial plan view of a stop-operated trip mechanism for the clutch controls in Figs. 10 and 11.

Fig. 13a-13f is an exploded view of one form of clutch employed in the machine.

Fig. 14 is a front elevation of part of the pulley and clutch assembly controlling the movable clip and a position indicator.

Fig. 15 is an axial section through Fig. 14.

Figs. 16 and 17 are an elevation and plan of a clutch pawl employed in the clutch shown in Figs. 13 to 15.

Fig. 18 is a diagrammatic representation of the method of coupling the clutch controls for the movable clip and the carriage.

Fig. 19 is a fragmentary plan view of a safety mechanism for interlocking the clutch controls for the drum, movable clip and carriage.

Fig. 20 is a rear elevation of a clip position indicator.

Fig. 21 is a part vertical section of Fig. 20.

Referring now to the drawings and more particularly to Figs. 1, 2, 3 and 6.

In the description the left-hand direction of travel of the clip and carriage viewed from the front of the machine will be referred to as forward travel, and the right-hand direction will be referred to as reverse.

The machine has main side frame members 1 and 2, and intermediate side frame members 3 and 4, these being interconnected and supported by cross members which are shown for example at 5, 6 and 7.

The drum 8 with its shaft 9 is shown supported in main bearings 10 at either side, and the lead screw 11, extending co-axially of the drum, has plain ends 12 and 13 extending beyond the drum, one of which carries a locating cam 14, to be described in more detail in the following.

The lead screw nut indicated generally by 15 carries a movable clip assembly, sunk in a recess of the drum, and indicated generally by 16, this being shown in its extreme forward position, and of a length approximating to half that of the drum. A fixed clip 17 extends over the right-hand half of the drum and is positioned behind clip 16, i. e. in front of the latter in the direction of rotation of drum 8, so that a fixed master in clip 17 may overlie a movable master in clip 16 in the well known manner. In Fig. 3 the drum is shown rotated away from the rest position, shown in Fig. 6, and is broken to reveal the clip and nut.

A pressure roller 18 and a damper 19 are mounted on a carriage adapted to be traversed lengthwise of the drum as a single unit as will be described in more detail hereinafter. In Fig. 3 the carriage is indicated in its extreme reverse position in which it projects to the right beyond the end of the drum while its left-hand end is approximately level with the drum centre. As an example of the relative dimensions the drum length may be 20 inches and the total pressure roller length 12 inches.

A hinged cover 20 extends across the machine over the damper and has a hole 21 through which a numbered scale 22 on the damper carriage may be observed for indicating the carriage position to the operator. A feed table 23 has a transparent panel 24 through which a front delivery tray 25 may be observed, and is slotted at 26 for lateral adjustment of a lay guide 27, which, with the adjustable back stop 28 determines the feed position of the work. A transparent panel 29 extends across the machine in front of the drum, and, together with plate 56, forms a feeding guide for the master sheets.

Referring now more particularly to Figs. 6 to 9 the pressure roller and damping carriage unit comprises a main frame casting 30 traversable across the machine by a lead screw 31 and nuts 32 and supported rearwardly by roller 33 which runs on a fixed transverse rail (not shown). The damping carriage is supported forwardly by the damping carriage rollers 34 running on a square guide rail 35, the rollers 34 being carried in a bearing member 36, and the damping assembly shown in Fig. 9 is so mounted as to have a small pivotal motion imparted

to it by square rail 35, but is movable lengthwise with the roller 18 as a unit.

A capillary damping pad 37 gripped in a comb-shaped clip 38 is removably fitted between end plates 39 and 40 of the carriage, and is supplied with damping liquid (solvent) by means of a spray tube 41 with downwardly directed holes 42, the spray tube being connected by a flexible tube 43 to pump 44 (Fig. 2). A pump priming hand lever 45 is connected through a linkage 46, 47, to supply a solvent initially or for intermittent operation. During rotation of the drum automatic pumping is effected by a cam roller 48 carried by the drum shaft operating, through cam ended bell crank 49 (Fig. 2) and linkage 50, 51, 52, on the pump bell crank 47, the lower end of which moves in a slot 53 in link 46. The capillary pad controls the amount of solvent taken up and any excess solvent is removed by a trough 54 (Fig. 6) discharging through a flexible tube 55 (Fig. 2).

The damping of the copy sheet is effected by a steel roller 60 extending the full width of the machine and driven from a drum gear wheel 59 through an intermediate reversing pinion engaging spur gear 61. Roller 60 co-operates with a pivotally mounted counter pressure roller 62 of the same length to form a pair of feed rollers 25 feeding the moistened sheet to the printing couple constituted by drum 8 and roller 18. Roller 62 is carried in bearings in bell cranks 63 pivoted in the machine frame (Figs. 1 and 2) at either side for movement towards and away from roller 60. In the rest position of the drum the rollers are separated by a gap as shown in Fig. 6, and the bell cranks 63 are cam operated in the initial movement of the drum from its rest position to close the gap. This is effected by means of a cam 64, cam roller 65 carried by lever 66 fast on square shaft 35, operating through cranks 67, 67a and connecting rods 68, to raise the roller 62 so as to grip the moistened sheet between the feed rollers. At the same time as the sheet is gripped, the lever 66 rotates the square shaft 35 carrying the damper sufficiently to bring the damping pad into contact with the applying roller 60. The positions of the roller 62 and the pad are restored by the cam 64 before the end of each drum rotation.

The motion of lever 66 derived from the drum through cam 64 also serves to actuate through crank 67a a safety 45 interlocking mechanism for the controls of the drum, clip and carriage, which will be described in more detail hereinafter.

A mechanism is provided for opening the movable clip 16 for reception of the master sheet only when the clip is 50 in the fully forward position, i. e., at the left-hand end, and only in the rest position of the drum i. e. as shown in Fig. 6. Referring now to Figs. 3, 5 and 6, this mechanism comprises a shaft 70 (Fig. 6) extending lengthwise of and journaled in the drum, and carrying a series of fingers 71 55 rigidly secured to the shaft 70, aligned axially, and spaced along the length thereof, which fingers in the full forward position of the clip 16, are immediately above and in line with a series of similarly spaced plunger pins 72 for actuating the clip blade 73. The shaft 70 extends beyond the 60 left-hand end of the drum and it carries a striker cam 74, which in the rest position of the drum lies adjacent a bell crank 75, constituting the end member of a linkage lying behind the linkage 49, 50, 51 in Fig. 2 and similar to that described above for automatic operation of the pump and 65 operating about the same fixed pivot centres 58 and 78. whereby the clip 16 may be opened by a hand lever 76 at the left-hand side of the machine. The first link 77 connecting the hand lever 76 to the clip operating linkage is shown in Fig. 2. After insertion of the master sheet between panel 29 and guide plate 56 into the open blade 73 of the clip, the hand lever is released and the blade is spring returned to grip the edge of the master sheet.

An exactly similar mechanism to that just described 75 consisting of a hand lever 81 (Fig. 3), link 82 (Fig. 5), bell crank 84 and a linkage pivoted on the centres 58, 78,

and actuates a striker cam 83 for opening the fixed clip, the construction of which is similar to that of the movable clip as regards fingers similar to fingers 71 and plunger pins similar to 72. The fixed clip and its opening mechanism are therefore not shown in detail in the drawing. The opening mechanism for the fixed clip is again arranged so that opening is only possible in the rest position with respect to the length of the drum but since the clip is always in a fixed position the lifting fingers are always in line with and adjacent to the pins, when the drum is in the rest position shown in Fig. 6.

The driving and control mechanism for the drum is shown in Fig. 2 and Fig. 5. The motor 90 drives the drum shaft through pulleys 100, 101, 102, 103 and fibre spur gears 104 and 105, the latter being clutched to the drum for a single or any number of consecutive revolutions by the following mechanism.

A ratchet 106 fast on the drum shaft is engageable by a spring pawl 107 pivoted on the gear wheel 105. The pawl is normally held out of ratchet engagement by a bell crank 108 freely pivoted on the main frame at 109 and resting on a pivoted latch 110, connected through connecting rod 111 and cranks 112, 118 (Fig. 1), fast on a common shaft to a Bowden control 113 at the right-hand side of the machine, the cable connector being omitted to clarify the drawing. The Bowden control is operated from the push bar 114 through a spring-return U-shaped plate 115 slotted at 116 to move on screws 117. Depression of plunger 114 acts through Bowden control 113 to pull the latch 110 to the left, thereby allowing the pawl to engage the ratchet and to drive the drum. Before the end of a complete revolution a roller 120 carried by the bell crank is engaged by cam 121 (Fig. 5) carried by the drum to disengage the pawl. The pawl being disengaged, the final movement of the drum under its own momentum to complete one revolution allows the roller 123, carried by a spring urged lever 124, pivoted in the side frame at 125, to snap into a recess of a cam 122, fast on the drum, thus preventing further rotary motion of the drum. In this position a freely pivoted hook 126 falls over a pin 127 carried by the drum, and the joint action of the said hook and the cam and roller serves to stabilize the drum in the rest position.

A flexible coupling and locating device is provided to couple the drum 8 and the lead screw 11 when the drum rotates during printing and to allow relative rotation of the lead screw when the latter is being driven. Referring to Figs. 2 and 5, the coupling comprises a ring 140 fast on the drum shaft and carrying a lever 139 pivoted thereto by an eccentric screw 141, which lever is loaded by spring 142 to seat a cam roller 143 in the recess of heart cam 14 fast on the lead screw shaft 12 and projecting to the left through the centre of ring 140. When the lead screw only is driven the drum is fixed in the rest position and the heart cam rides off the cam roller 143 and at the end of each revolution is located in the cam recess. It will be understood that the action of the coupling depends on the difference in inertia between the drum which carries ring 140, and the lead screw and heart cam 14 of much smaller mass. When the drum is rotated as above described, the lead screw represents a comparatively small load and is carried round with the drum, the spring 142 exerting sufficient tension to keep the roller 143 engaged in the recess of the heart cam 14. The type of coupling here described cannot function with simultaneous drive to the clip and drum, and means for preventing this will be described hereinafter.

The power transmission for the movable clip and the pressure roller-damping carriage unit may be seen in Figs. 1, 2 and 4. The driven shaft 150 extends across the machine and carries a pulley 151 driving the pulleys 152 and 153 clockwise, these pulleys being fast on the driving members of one-revolution clutches controlling the reverse drive of the carriage and the clip respectively. Pulley 151 carries a spur gear 154 engaging spur gear 155 on

pulley 156, which drives a pulley 157 counter-clockwise on the same centre as pulley 152 and a pulley 158 on the same centre as pulley 153. These pulleys carry the driving members of further one-revolution clutches controlling the traversal of the carriage and the clip respectively in the forward direction. 159 is a guide pulley for the drive from pulley 156.

Various forms of escapement may be employed for controlling the motion of the clip and the carriage, but it is preferred to use the same kind of clutch for controlling both the carriage and the clip for forward and reverse drive. A preferred form of clutch is shown disassembled in Figs. 13a to 13f, and a modified clutch assembled to the pulley is shown in end elevation and section in Figs. 14 and 15. An elevation and plan of the clutch pawl are shown in Figs. 16 and 17. The clutch and pulley assembly illustrated in Figs. 14 and 15 is that used to control the forward drive of the movable clip or the carriage both for continuous traversal and for single spacing, but the details of the clutch itself are identical with those of the clutches employed for the reverse motion of the carriage and clip, except that the clutch in Figs. 14 and 15 incorporates a housing in the form of a bevel gear which co-operates with a planetary gear for driving a position indicator to be described hereinafter.

In Figs. 13a to f, 13a shows the clutch housing, 13b the pawl assembly, 13c the driven member, 13d the driving member, 13e the housing cover plate and 13f part 30 of the shaft.

In Figs. 13 and 14 to 17, the pulley 158, secured to driving member 160, is free on the end 13 of the lead screw shaft. The driven member 161 is keyed to the shaft by a key 162a extending through keyway 162. The clutch housing 163 in Fig. 13a, and 163a in Fig. 15, is normally not clutched to either the driving or the driven member. The housing carries a pawl 164 pivoted thereto by pins 165, and urged in a counter-clockwise direction about pivot 165 by a spring 166 connected at one end 40 to the pawl and at the other end to the clutch housing. The pawl is in two halves on either side of a vertical dividing plane (Fig. 17) and has a tooth 167 and a notch 168 formed in one half and a tooth 169 and notch 170, in staggered and opposite relation to tooth 167 and 168, in the other half. The driven member has a tooth 171 in the same plane as, and co-operating with notch 170. The driving member 160 has two teeth 172 and 173 in the same plane as, and co-operating singly with notch 168. The pawl, and the driving teeth of the driving and driven members, are enclosed between the clutch housing 163 or 163a and the cover plate 174 (Fig. 13e) or 174a (Fig. 15).

In the "clutch disengaged" position the nose of the pawl is engaged by the arm of a lever 180 (see Fig. 11), whereby the pawl is pulled against the action of the spring 166 out of engagement with both the driving and driven members of the clutch. When the lever 180 is disengaged the spring 166 rotates the pawl about pivot 165 pulling the respective notches into engagement with 55 the teeth of the driving and driven members, whereby the lead screw shaft is rotated. When the lever 180 is allowed to return, the nose of the pawl will re-engage the end of lever 180 at a given point of its existing revolution, and thereby disengage itself from the driving and driven members. At the end of a complete revolution a spring urged bell crank 181 (Fig. 11) engages a cam notch 183 of clutch housing 163. The clutch housing is thereby stabilized in the disengaged position.

The clutch cover plate 174a, Figs. 14 and 15, is in the form of a cam 185 being part of a single spacing control 70 to be described in more detail in the following.

The clutch control mechanism for the carriage is indicated generally in Fig. 1 by the reference 200 and the clutch control mechanism for the movable clip is indicated generally in Fig. 1 by the reference 300, the main 75

components of these clutch control assemblies being similar in each case and varying only in two respects which will be described in more detail in the following.

One of the clutch control mechanisms will be described in detail, namely, the clutch control mechanism for return travel of the movable carriage, a part elevation of this mechanism being shown on a larger scale in Fig. 10. On the fixed pin 99 secured to the right-hand frame member of the machine, is pivoted a triangular crank plate 186 carrying the integral lever arm 180. On the same pivot centre is the bell crank 181 urged in the clockwise direction by spring 187. Plate 186 is pulled in the counter-clockwise direction by spring 188 and carries at its lower end pins 189 and 190 on opposite sides thereof. A notched lever 191 is pivoted at 192 on lever 193 which is itself pivoted on a fixed pivot post 194 secured to the frame. A further bell crank 195 carrying a pin 196 is also pivoted on the post 194 (Figs. 10 and 12). The said lever is controlled by a Bowden cable 197 anchored at one end to a fixed bar 201 in the frame. The other end of the Bowden cable is connected to a stop mechanism to be further described herein. The lever 193 is controlled by a Bowden cable 198, one end of which is anchored in fixed bar 199 and the other end of which is connected to the respective one of a set of push-button keys in a control panel mounted at the right hand side of the machine and indicated by the general reference 250 in Fig. 1. Upon depression of the respective key the lever 193 pushes the notched lever 191 to the left against the tension of spring 202 and engages a notch of the lever with the pin 190 of plate 186, which is thereby rotated clockwise to disengage the lever 180 from the nose of the pawl 164, in which position the mechanism is shown in Fig. 10. This operation engages the clutch as already described above, and at the same time a locking hook 205 freely pivoted at 206 falls over the pin 189 and locks the plate 186 in the "clutch engaged" position. So long as hook 205 is locked the lead screw of the carriage will rotate clockwise viewed in Fig. 1 and, assuming the lead screw is right-hand, the carriage unit will travel to the right, i. e. in reverse, and this travel will continue whether the push button key is released or not.

Stop means are therefore provided at the end of the reverse travel of the carriage to disengage the clutch automatically and bring the carriage to rest. The automatic stop mechanism comprises a spring stop 210 fixed at the inside of the main frame and connected to the other end of Bowden cable 197. Depression of the right-hand spring stop by the carriage just before its end position operates the Bowden control to depress the bell crank 195, which lifts the notched lever 191 against spring 208 by means of the pin 196 thereby releasing plate 186 and disengaging the clutch and at the same time lifting hook 205 from pin 189 by means of the pin 207 carried on the hook, which then falls into the position shown in dotted lines.

In order to provide for single spacing as well as continuous travel of the clip and carriage, an additional control device may be provided for the clutch controlling the forward or reverse drive or both. In the machine described both single spacing and continuous travel are provided for the forward direction of the clip and the carriage, reverse single spacing having been found not essential for most functions of the machine.

The main elements of the continuous travel and single spacing control for forward drive of the carriage are shown in Figs. 11 and 12, these being mounted immediately behind the control mechanism shown in Fig. 10, as seen in Fig. 1, since both clutches are co-axial with the lead screw shaft.

The clutch is identical with that shown in Figs. 14 and 15, except that the clutch housing does not include the bevel gear face on the clutch housing. In Fig. 11 parts 181, 186, are again mounted on the pivot pin 99, and are identical with those parts in Fig. 10, except that they are reversed; as is also the clutch, in conformity with the

counter-clockwise drive to the pulley. The direction of spring tension on these parts is also reversed as shown by springs 211, 212.

The clutch control device for continuous travel comprises notched lever 213 pivoted in lever 215, itself pivoted on post 194. Manual control is effected from the control panel 250 by one of the push-button keys through a Bowden cable in a manner equivalent to that described above for the reverse control shown in Fig. 10, the notch 216 of lever 213 pulling plate 186 counter-clockwise and thus engaging the clutch. In this case however the clutch is not locked in the "engaged" position, and the carriage will be arrested at the end of an existing revolution as soon as the push-button key is released.

For single spacing control a second notched lever 219, longer than lever 213, is pivoted at 218 in a lever 221 and has a notch 222 co-operating with pin 190. The clutch is controlled by another push button key through a Bowden cable the end 223 of which is anchored at 224. The clutch is engaged through levers 221, 219 and 180 in a manner equivalent to that above described. The clutch is, however, positively disengaged, to give only one revolution, by means of cam 185 and trip lever 225. The latter is pivoted on pin 99, and is connected to the end of lever 219 through a link 226, so that when the clutch is engaged for single space motion of the carriage, the end of lever 225 is placed in the path of cam 185. The clutch is thereby positively disengaged whether the respective push button key remains depressed or is released.

The automatic stop mechanism for declutching at the end of forward travel is similar to that described for reverse travel with respect to Fig. 10, except that the bell crank 227 lifts both levers 213 and 219 simultaneously by pin 228 when operated from the left-hand stop 229 (Fig. 2) through Bowden cable 230. The mechanism is shown in this position in Fig. 11, the carriage having reached the forward end position.

In order to achieve rapid positioning of the movable clip and the carriage, means are provided for coupling the clutch controls so as to provide simultaneous travel of the movable clip and the carriage either in the same direction, or in opposite directions with combinations of single spacing and continuous travel as desired.

The control panel 250 for the clutches comprises six push button keys and it will be assumed that these are indicated by A, B, C, D, E and F respectively. This number is provided, since in the machine described clutch controls are provided for obtaining three different modes of travel of both the movable clip and the carriage. One possible scheme of coupling the individual clutch controls is indicated diagrammatically in Fig. 18, wherein eight push levers indicated by 261—268 respectively are shown mounted on a fixed pivot 260, 264 and 266 being coupling levers, and the remaining six each being connected by a Bowden cable to the respective clutch. Lever 261 controls the clutch for continuous forward travel of the carriage; lever 262 controls the clutch for continuous forward travel of the movable clip; lever 263 controls the forward single spacing of the carriage; lever 265 controls the clutch for forward single spacing of the clip; lever 267 controls the clutch for continuous reverse motion of the carriage; lever 268 controls the clutch for continuous reverse motion of the clip.

It will be apparent from the description above with relation to the clutch controls that for both the clip and the carriage single spacing or continuous movement is provided in the forward direction, whereas in the reverse direction the carriage performs continuous motion until it reaches its fully reversed position, this preferably corresponding to the initial printing position. On the other hand continuous reverse motion of the clip will be performed so long as the appropriate clutch control is operated and will cease as soon as that control is released.

For such a scheme of clutch control it is appropriate to couple the clutch controls as indicated diagrammat-

ically in Fig. 18 in which a coupling bar 270 bridges the levers 261 and 262, a further coupling bar 271 bridges the levers 263, 264 and 265, a further coupling bar 272 similarly bridges the control levers 265, 266 and 267, and finally a coupling bar 273 bridges the levers 267 and 268.

For the purpose of description it will be assumed that push button key A is connected to coupling bar 270; hence depression of this key will operate the clutch controls giving continuous forward motion of both the carriage and the master clip until the key is released.

Key B is connected to coupling bar 273, depression of this key simultaneously operating the clutch controls giving full reverse of the carriage to the initial printing position and continuous reverse travel of the clip, either partially if the key is released, or full reverse travel if the key remains depressed.

Key C is connected to coupling bar 272, depression of this key simultaneously operating the clutches giving full reverse of the carriage and moving the clip one space forward. Any subsequent depression of the same key moves the clip one further space forward but leaves the carriage in its fully reversed position.

Key D is connected to the coupling bar 271, and depression of this key simultaneously operates the clutches moving the carriage and the clip each one space forward.

Key E controls lever 263 only, and depression of this key will operate the clutch moving the carriage one space forward.

Key F is connected only to control lever 265 and the depression of this key will engage the clutch moving the clip one space forward.

The normally required movements of the carriage and clip may be controlled by the operation of the four keys namely A—D. The keys E and F provide additional control in the form of single forward spacing of the carriage and clip.

It is necessary to insure that motion of the drum shall only take place whilst the carriage and movable clip are stationary and vice versa. This is provided for by a safety mechanism interlocking the controls of the drum the carriage and the clip, this mechanism being shown in elevation in Fig. 1 and in partial plan in Fig. 19.

The push bar 114 controlling the drum clutch is spring returned by means of a bell crank 280 pivoted to the frame and having a forked end 281 engaging a pin 282 secured to a limb of the U-plate 115, the other arm of the bell crank being connected to a spring 283 anchored to the frame. A pin 284 at the end of the bell crank is located in a slot 285 in a push bar 286 to which is secured a masking plate 287 (Fig. 19) having six circular holes 288 larger than, but concentric with the heads of the push button keys. The plate 287 is guided for forward movement by means of slots 289 co-operating with guide screws 290.

A hook 291 pivoted in the frame at 292 is urged clockwise by the spring 293, and is loosely connected by a hooked rod 294 to a pin 296 in lever 67a, which lever is controlled by lever 66 and drum cam 64 as described above.

The upper end of push bar 286 is slotted to slide over pin 296 on lever 67a, and is urged to the left by a spring 296 anchored to lever 67a and to push bar 286.

In the rest position of the machine the hook 291 is disengaged as shown in Fig. 1.

If push bar 114 is depressed, with the motor running, the drum clutch engages, as described above. Cam 64 and lever 66 operate in the initial motion of the drum to mask the push button keys, this action being effected through lever 67a and push bar 286. The masked position in which the keys cannot be depressed is shown in dotted lines in Fig. 19. The plate 287 is restored by the drum cam just before the end of the revolution.

If push bar 114 is accidentally depressed without the motor running, the drum clutch engages, but at the same

time hook 291 locks over pin 281, and the push button keys are masked as before. If now the motor is switched on, the drum will rotate at once, and in completing one revolution will restore the safety mechanism.

If the push-button key controlling the full reverse of the carriage is depressed when the machine is at rest, the head of this key will remain depressed since, as above described, the clutch control is locked by the hook 205 (Fig. 10) until the carriage has fully reversed. The depressed key will therefore prevent any horizontal motion of the masking plate 287 and will therefore lock the push bar 114, thus preventing rotation of the drum. The locked condition can be cleared by fully reversing the carriage.

In the case of those push button keys, which control other modes of movement of the clip and the carriage and which do not lock down in the depressed position, but are spring returned as soon as the key is released, the above described locking of the drum clutch control will, however, be operative, since whilst any one of them is depressed, masking plate, and hence the drum clutch control mechanism, cannot be operated.

A position indicating device is preferably incorporated in the machine to display the position of the movable clip to the operator, and one form of such an indicator is illustrated diagrammatically in Figs. 20 and 21.

A replica of the master carried on the movable master sheet, which replica may be an actual copy taken from the master, is mounted on the front panel of a framework 305, visible to the operator, by means of a spring clip comprising a horizontal rod 303 carrying a series of spaced rollers 302, the rod being pivotally mounted at either side and pressed by springs 304 into engagement with the top edge of the replica 301.

A horizontal indicator bar 306, preferably of transparent material, is supported at each end on brackets projecting through vertical slots 307, 308 in the panel 305 and carrying nuts 309 and 310 mounted on lead screws 311 and 312, the latter being connected by bevel gears 313 to a horizontal shaft 314. Rotation of the shaft 314 in fixed relation to the motion of the movable clip will traverse the indicator bar 306 vertically and therefore give an indication of the position of the movable clip. Shaft 314 carries a spur gear 315, connected through a pinion 316 to planet carrier 317 of a differential gear, the bevel planet wheels of the planet carrier 317 engaging at each side thereof a bevel gear 318 (see Fig. 15) on the respective clutch housing controlling the forward and reverse motions of the movable clip. When either one of the members 318 is driven the indicator bar 306 will be vertically traversed in one or the other direction. It is preferably arranged that the indicator bar 306 is in its topmost position when the movable clip is in the initial printing position.

In the foregoing description the operation of stops, located in the machine frame, has been described for arresting the movable carriage in its end positions. Although similar end stops may be provided in the machine frame for disengaging the clutches controlling the movable clip, it is preferred to incorporate the end stops for the movable clip in the position indicator device described above with reference to Figs. 20 and 21. The arrangement comprises spring stops 320 and 321 mounted on fixed brackets 322, 323 at the top and bottom of the frame 305, these stops being connected to Bowden cables 324, 325, respectively connected to a clutch control device for the reverse and forward drive of the movable clip. Such clutch control devices operate in substantially similar manner to those for the carriage which have been described above with reference to Figs. 10, 11 and 12. Consequently operation of the stops 320 and 321 of the indicator by nut 310 will disengage the respective clutches and arrest both the movable clip and the indicator.

It is often necessary for production control purposes to print a series of tickets each consisting of a heading contained on a fixed master together with a different single

item from a movable master, and to take a further impression comprising the same heading on the fixed master plus the whole of the matter on the movable master. The operation of the machine will now be described for such an operation, the movable master having a length equal to half the length of the drum.

The fixed master and movable master are fed between the panel 29 and the guide 56 to their respective clips, the drum being in the rest position and the respective clips having been moved to their appropriate positions. By operating the clip opening mechanisms the movable and fixed master are gripped therein and are positioned to be wrapped round the drum.

An impression is taken with the movable clip and the carriage in their fully forward positions, this impression including the heading on the fixed master and all the items on the movable master. The movable clip and the carriage are now placed in their fully reversed position, corresponding to the initial printing position, in which the pressure roller is set to cover the first item exposed beyond the edge of the fixed master. A succession of impressions is now taken, the movable master being exposed stepwise beyond the edge of the fixed master. These operations are carried out from a fixed feeding position and a fixed delivery position determined by the guide 27 and stop 28. The adjustment of the pressure roller and damping unit to account for possible varying widths of the exposed areas of the movable master, is effected from the control panel by the appropriate push button keys hereinbefore described, these giving the required combination of movements of the movable clip and carriage to bring these into their positions for the different impressions with the minimum movement of the machine and operator.

The printed tickets are delivered from the printing couple to an inclined tray 331 (Fig. 6), and descend to pass over a delivery roller 332, friction driven by the belt and pulley transmission of the drum at the left side of the machine. The tickets pass between the roller 332 and a series of spaced balls 333 resting thereon and are delivered at the front delivery tray, stacked in the order of printing.

A device cooperating with the clutches to ensure proper location of the carriage lead screw shaft in the rest position is shown in Figs. 7a and 8, Fig. 7a being part of a front elevation. Lead screw shaft 35a carries cam 31a fast thereon. The rest position of cam 31a, and hence of shaft 35a and the driven clutch member 161 (Fig. 15), is adjustable by means of arm 31c carrying cam roller 31a and pivoted on the eccentric screw 31b. Adjustment of screw 31b will therefore adjust the relative position of clutch member 161 with respect to the clutch housing 163 and pawl 164 (Fig. 15). This is similar to the adjustment provided by eccentric screw 141 (Fig. 5) for the clip lead screw.

We claim:

1. In a rotary hectographic copy machine, a rotatable printing drum, a first clip adapted to take a fixed master sheet, a second clip adapted to take a movable master sheet, means for holding said drum in a rest position, and means for positively traversing said second clip in either direction parallel to the drum only when the drum is at rest comprising a clip drive shaft passing co-axially through the drum, a coupling between said drum and the clip drive shaft, said coupling having a member secured to the drum and a co-operating member secured to the shaft, said coupling members being in engagement in only one angular position of the clip drive shaft relative to the drum, means for driving said drum and means for driving the clip drive shaft and resilient means connecting said coupling members to allow said clip drive shaft to overrun the drum when the drum is held at rest.

2. In a rotary hectographic copy machine, a rotatable printing drum, a first clip adapted to take a fixed master sheet, a second clip adapted to take a movable master

sheet, means for holding said drum in a rest position, and means for positively traversing said second clip in either direction parallel to the drum only when the drum is at rest, comprising a clip drive shaft passing co-axially through the drum, means for driving said clip drive shaft, a coupling between said drum and the clip drive shaft, said coupling having a member secured to the drum and a member secured to the clip drive shaft and means therebetween for resiliently engaging said coupling member, one of said coupling members being a locating cam defining a single angular position of the shaft with respect to the drum, said engaging means allowing slipping of said coupling to allow the clip drive shaft to rotate when the drum is held at rest.

3. In a rotary hectographic copy machine, a rotatable printing drum, a first clip adapted to take a fixed master sheet, a second clip adapted to take a movable master sheet, means for holding said drum in a rest position and means for positively traversing said second clip in either direction parallel to the drum only when the drum is at rest comprising a rotatable clip drive shaft passing co-axially through the drum, means for driving said clip drive shaft and means for driving the drum; a slipping coupling between the drum and the clip drive shaft said

coupling comprising a single dwell cam and a cam roller and resilient means normally holding said coupling members in engagement and allowing slip of said coupling when the clip drive shaft is driven and the drum is held at rest.

4. In a rotary hectographic copy machine, a rotatable printing drum, a first clip adapted to take a fixed master sheet, a second clip adapted to take a movable master sheet, means for holding said drum in a rest position and means for positively traversing said second clip in either

direction parallel to the drum only when the drum is at rest comprising a clip drive shaft passing co-axially through the drum, means for driving the drum, separate means for driving the clip drive shaft in opposite directions said means including a driving shaft for each direction and a clutch for coupling each of said driving shafts to the clip drive shaft, a slipping coupling between the drum and the clip drive shaft said coupling having a member attached to the drum and a member attached to the shaft and resilient engaging means for said coupling members allowing slip of said coupling for independent driving of the clip drive shaft in either direction when the drum is held at rest.

5. In a rotary hectographic copy machine, a rotatable printing drum, a first clip adapted to take a fixed master sheet, a second clip adapted to take a movable master sheet, means for driving the drum, means for holding said drum in a rest position and means for positively traversing said second clip in either direction parallel to the drum only when the drum is at rest comprising a rotatable clip

drive shaft passing co-axially through the drum, means for driving the clip drive shaft in either direction said means including a driving shaft and a one-revolution clutch for each direction of rotation and means for selectively engaging said clutches with the clip drive shaft, a resilient coupling between the drum and the clip drive shaft said coupling having a member attached to the drum and a member attached to the clip drive shaft, said members being normally engaged when the drum is at rest and the one-revolution clutches are disengaged, said coupling allowing slip between said coupling members to allow the clip drive shaft to rotate within the drum when said clip drive shaft is driven through either one of said one-revolution clutches and the drum is held at rest.

6. In a rotary hectographic copy machine, a rotatable printing drum, a first clip adapted to take a fixed master sheet, a second clip adapted to take a movable master sheet, means for holding said drum in a rest position, and means for positively traversing said second clip in either direction parallel to the drum only when the drum is at rest comprising a clip drive shaft passing co-

axially through the drum, means for driving the drum, separate means for driving the clip drive shaft in either direction said means including a one-revolution clutch for each direction of rotation a resilient coupling between the drum and the clip drive shaft said coupling having a member attached to the drum and a member attached to the clip drive shaft, said members being normally engaged to hold said clip drive shaft at rest and coupled to the drum when both one-revolution clutches are disengaged, and said coupling allowing the clip drive shaft to rotate relative to the drum when the said shaft is driven each of said one-revolution clutches having a pawl device through which the said clip drive shaft is driven in the respective direction and means for releasing said pawl devices at one point in the clutch revolution to allow the coupling between the drum and the clip drive shaft to re-engage when the clip drive shaft has completed an integral number of revolutions from its rest position.

7. In a rotary hectographic copy machine, a rotatable printing drum, a first clip adapted to take a fixed master sheet, a second clip adapted to take a movable master sheet, means for holding said drum in a rest position, and means for positively traversing said second clip in either direction lengthwise of the drum only when the drum is at rest comprising a rotatable clip drive shaft passing co-axially through the drum shaft, means for driving the drum, separate means for driving said clip drive shaft when the drum is at rest and a coupling between said shaft and the drum said coupling having coupling members on the said shaft and on the drum shaft, and resilient means holding said coupling members engaged when the drum is driven, said coupling members being disengaged when the clip drive shaft is driven.

8. A machine according to claim 7 comprising the combination of a lead screw connected to the said clip drive shaft, a nut carrying the movable clip in engagement with said lead screw and wherein the coupling between the drum and the clip drive shaft comprises a recessed cam and a spring urged roller co-operating with the cam recess.

9. A machine according to claim 8 wherein the driving means for the clip drive shaft comprises a motor, two driving shafts driven by said motor in opposite directions and a one-revolution clutch between each driving shaft and the clip drive shaft said clutches providing equal unitary displacements of the clip in opposite directions.

10. A machine according to claim 9 wherein each one-revolution clutch comprises a clutch pawl, pawl-engaging clutch members on the driving shaft and the clip drive shaft respectively, a lever for normally retaining said pawl in a position in which it is disengaged from the clutch member on the driving shaft and disengaged from the stationary clutch member on the clip drive shaft, said clip drive shaft being retained in the position in which said pawl-engaging clutch member on the clip drive shaft is ready for engagement with the pawl by means of the said cam and roller coupling between the clip drive shaft and the drum, manually operable means for releasing said lever to allow said pawl to engage both clutch members, and means restoring said lever to normal.

11. A machine according to claim 9 comprising for at least one of the clutches a manually operable control lever causing engagement of the clutch in combination with a clutch throw-out device comprising a cam and a trip lever operated by said cam within the first revolution of the clip drive shaft to disable said control lever and disengage the clutch thereby to provide a single stepwise displacement of the clip for each actuation of the said control lever.

12. A machine according to claim 7 including guide rails arranged parallel to the drum, a carriage mounted on said guide rails and a pressure roller and damping unit providing co-extensive pressure and damping over a length at least equal to half the length of the drum

mounted on said carriage for movement lengthwise of the drum.

13. A machine according to claim 12 including means for traversing said carriage comprising a lead screw, two oppositely rotatable driving shafts, a one revolution clutch between each driving shaft and the lead screw and means for selectively engaging said clutches.

14. A machine according to claim 13 including for at least one of said clutches, a manually operable clutch engaging lever, a locking lever for locking said clutch engaging lever in the clutch engaged position, a stop in the path of said carriage, and means actuated by said stop to release the locking lever.

15. A machine according to claim 13 including for at least one of said clutches a manually operated control lever for causing engagement of the clutch and a clutch throw-out device comprising a cam and a trip lever actuated by said cam within the first revolution of the lead screw to disable said manually operated control lever to disengage the clutch and thereby to provide unitary stepwise displacement of the carriage for each actuation of the said control lever.

16. In a rotary hectographic copy machine, a rotatable printing drum, a first clip adapted to take a fixed master sheet, a second clip adapted to take a movable master sheet, means for driving the drum, means for holding said drum in a rest position and means for positively traversing said second clip in either direction parallel to the drum only when the drum is at rest comprising a rotatable clip drive shaft passing co-axially through the drum, means for driving the clip drive shaft in either direction said means including a driving shaft and a one-revolution clutch for each direction of rotation and means for selectively engaging said clutches with the clip drive shaft, a resilient coupling between the drum and the clip drive shaft said coupling allowing slip between said coupling members to allow the clip drive shaft to rotate within the drum when said clip drive shaft is driven through either one of said one-revolution clutches and the drum is held at rest, at least one manual control lever for said clutches, a drum start control member for said drum and a mechanical interlock between said drum start control member and said manual control lever to prevent simultaneous operation thereof.

17. In a rotary hectographic copy machine, a rotatable printing drum, a first clip adapted to take a fixed master sheet, a second clip adapted to take a movable master sheet, means for holding said drum in a rest position, and means for positively traversing said second clip in either direction parallel to the drum only when the drum is at rest, comprising a clip drive shaft passing co-axially through the drum, means for driving said clip drive shaft, a coupling between said drum and the clip drive shaft, said coupling having a member secured to the drum and a member secured to the clip drive shaft and means therebetween for resiliently engaging said coupling members, one of said coupling members being a locating cam defining a single angular position of the shaft with respect to the drum, said engaging means allowing slipping of said coupling to allow the clip drive shaft to rotate when the drum is held at rest, means for driving the drum comprising a motor driven shaft, a clutch between the motor driven shaft and the drum shaft, a drum start control member for actuating said clutch, and a mechanical interlock between said drum start control member and the clip drive shaft for preventing simultaneous operation thereof.

18. In a rotary hectographic copy machine, a rotatable printing drum, a shaft for said drum a first clip adapted to take a fixed master sheet, a movable clip adapted to be moved lengthwise of the drum, means for holding said drum in a rest position; means for positively traversing said movable clip in either direction when the drum is at rest comprising a lead screw passing co-axially through the drum shaft, two oppositely

rotatable driving shafts, a one-revolution clutch between each of the driving shafts and the lead screw and control means for selectively engaging said clutches; and means for selectively applying moisture and printing pressure during each copying operation comprising a second lead screw arranged parallel to the drum, a driving shaft for the second lead screw, a carriage mounted on said lead screw, a combined pressure roller and damping unit mounted on said carriage and a drive shaft and clutch means for selectively rotating said carriage lead screw in either direction whilst the drum is at rest.

19. The machine as claimed in claim 18 including in combination with said carriage lead screw two oppositely rotatable driving shafts, a one-revolution clutch between each of said driving shafts and the carriage lead screw and manual control means for selectively engaging said clutches, and including means for effecting simultaneous movement of the movable clip and the carriage comprising at least one common control member coupling together a member for selectively engaging the clutches for the clip and a member for selectively engaging the clutches for the carriage.

20. The machine as claimed in claim 18 including a motor driven shaft for the drum, a clutch between the said driven shaft and the drum shaft, a drum start control member for actuating said clutch, at least one manual control member for a clutch controlling the clip lead screw and at least one manual control member for a clutch controlling the carriage lead screw and a mechanical interlock between said drum start control member and each of said manual control members for preventing simultaneous rotation of the drum with the movable clip or the carriage.

21. The machine as claimed in claim 18 including means for preventing rotation of the drum simultaneously with operation of either the movable clip or the carriage comprising a plurality of clutch control members, a plurality of push buttons each operatively connected to at least one clutch control member, a slideable masking plate having keyhole slots for said push buttons, and a drum start control member operatively connected to said masking plate, said masking plate when operated disabling all of the push buttons, and any one of said push buttons when depressed disabling the masking plate if the masking plate has not been operated by the drum start control member.

22. The machine as claimed in claim 21 including means for restoring the masking plate within each revolution of the drum comprising a cam secured to the drum shaft and a lever linkage between the drum cam and the masking plate.

23. In a hectographic copy machine a rotatable printing drum, a first clip adapted to take a fixed master sheet, a second clip to take a movable master of half the drum length spaced behind said first clip in the direction of drum rotation, means for holding said drum in a rest position, means for positively traversing said second clip by unitary steps through half the drum length to expose the movable master progressively beyond the edge of said fixed master whilst the drum is at rest and for positively traversing the clip in the reverse direction said traversing means comprising a lead screw shaft extending co-axially through the drum, a combined pressure roller and damping unit comprising a carriage traversable parallel to said drum and a damping pad and pressure roller of equal length equal to at least half the drum length, means for traversing said carriage independently of the movable clip between an initial printing position in which the pad and pressure roller extend beyond one end of the drum and register over at least the whole of the fixed master sheet and a final printing position in which the pad and pressure roller register over the whole of the movable master sheet and an adjoining portion of the fixed master sheet, and a

fixed feed table having an adjustable lay guide defining a constant lateral feed position for a series of copy sheets to be fed to the drum to take impressions from a constant portion of the fixed master and the whole or any portion of the movable master.

24. In a hectographic copy machine a rotatable printing drum, a first clip adapted to take a fixed master sheet, a second clip to take a movable master of half the drum length spaced behind said first clip in the direction of drum rotation; means for holding said drum in a rest position, means for positively traversing said second clip in either direction comprising a lead screw passing co-axially through the drum, and driving shafts and clutches for rotating said lead screw in opposite directions; a combined pressure roller and damping unit comprising a carriage traversable parallel to said drum, a damping pad and a pressure roller of equal length equal to at least half the drum length, and means for traversing said carriage lengthwise of said drum to apply damping fluid and printing pressure co-extensively over a variable zone which includes the fixed master and an adjacent portion of the movable master defined between the edge of the fixed master and the leading edge of the pressure roller and damping unit.

25. In a hectographic copy machine a rotatable printing drum, a first clip adapted to take a fixed master sheet, a second clip to take a movable master of half the drum length spaced behind said first clip in the direction of drum rotation; means for holding said drum in a rest position, means for positively traversing said second clip axially of the drum whilst the drum is at rest comprising a clip drive shaft passing co-axially through the drum, means for driving said clip drive shaft independently of the drum and releasable coupling means between said drum and clip drive shaft allowing simultaneous rotation of the drum and clip drive shaft during printing; a combined pressure roller and damping unit comprising a carriage traversable parallel to said drum, a damping pad and a pressure roller of equal length equal to at least half the drum length mounted on said carriage and means for traversing said carriage lengthwise of said drum to apply damping fluid and printing pressure co-extensively over a variable zone which includes the fixed master and an adjacent portion of the movable master defined between the edge of the fixed master and the leading edge of the pressure roller and damping unit.

26. A hectographic copy machine comprising a drum carrying a fixed clip adapted to secure a mask or a printing master and a movable master clip lying lengthwise of the drum and traversable lengthwise thereof when the drum is at rest, the movable clip being behind the fixed clip in the direction of rotation of the drum so that a master secured in the movable clip may be exposed for printing to a variable extent beyond the edge of an overlying master or mask in the fixed clip, and means for positively traversing said movable clip in both directions lengthwise of the drum whilst the drum is at rest comprising a lead screw extending co-axially of the drum and rotatable independently of said drum, a nut on the lead screw carrying said clip, and means for rotating the lead screw together with the drum at the same angular velocity so that the clip has no axial motion during the printing operation.

27. The machine as claimed in claim 26 including a power-driven shaft for the drum, clutch means associated with the said power driven shaft and means for locating the drum in a rest position, a resilient coupling between the drum and the lead screw shaft permitting the drum and the lead screw shaft to be rotated together when the drum shaft is driven, said coupling having a member secured to the drum and a member secured to the lead screw shaft said coupling members defining a single angular position of said lead screw shaft with respect to the drum, a first clip adapted to take a fixed master sheet, a

said coupling to permit independent rotation of the lead screw shaft when the drum is held at rest.

28. The machine as claimed in claim 26 including power driven means for rotating the drum comprising a motor driven shaft, a clutch between the motor driven shaft and the drum shaft, a drum start control member for actuating said clutch and mechanical interlocking means between said drum start control member and the lead screw shaft for preventing driving of the drum shaft when said lead screw shaft is being rotated for traversing the clip. 10
